Layman E. Dodge

UNITED STATES PATENT OFFICE.

BEVERLY A. LUNDY, OF LARCHMONT, NEW YORK.

ELECTRICAL CONNECTER.

Application filed September 3, 1927. Serial No. 217,325.

This invention relates to electrical conductors particularly to connectors therefor, and more especially to connectors for attaching a branch or tap to a line wire.

- 5 It is well understood by those skilled in the electrical art, and especially by those skilled in that branch thereof, known as electric railway signalling, that it is frequently necessary to position a conductor at one of 10 the poles positioned along a railroad track, which conductor is connected at one end to one of the line wires supported by the pole and at the other end is connected to an instrument positioned on or near the ground. 15 It is also well known that a great difference exists in the manipulative skill of workman in making a joint between a tap wire and a line wire and that failures have often occurred.
- 20 A principal object of this invention is to provide a device by means of which a most inexpert and careless workman may successfully make a thoroughly good joint between two conductors, especially between a 25 line wire supported on poles, and an adjacent wire connecting to an instrument on the ground near the pole line.

Other objects and advantages will appear as the description of the particular physical 30 embodiment selected to illustrate the invention progresses, and the novel features will be particularly pointed out in the appended claims.

- In describing the invention in detail, and 35 a particular physical embodiment selected to illustrate the invention, reference will be had to the accompanying drawings, and the illustrative figures thereon in which similar characters of reference refer to like parts 40 throughout the several views and in which:

Figure 1 is a schematic view illustrating a pole line and a tap connected to one of the wires thereof by the use of the invention; Fig. 2 is a cross sectional elevational 45 view of a device embodying the invention and showing two conductors connected thereby; Fig. 3, is an end view of the device as shown by Fig. 2.

In Fig. 1, the numeral 1, designates a pole 50 to which is attached the cross arm 2, having a plurality of insulators, as 3, supporting line wires 4, 5, 6, 7 and 8.

9 designates a conductor which connects electrically with line wire 7 and is shown as 55 connected thereto by means of a device em-

bodying applicant's invention and designated generally by 10.

In order to make the connection between the line wire 7 and the conductor branch or tap 9, the line wire 7 is fastened securely at 60 its end about the insulator 3, and has a portion 11 extending upwardly toward the device 10. The conductor 9 also extends upwardly and into the device 10, and is supported by any suitable form of clip as 12. 65

In order to make the electrical connection between the extension 11 of the line wire 7 and the conductor 9, the ends of both are bared for a certain distance as shown most clearly in Fig. 2, in which the bared end 70 11 is designated 13 and the bared end of 9 is designated 14.

After the ends of the conductors 9 and 75 11 are bared as explained, they are pushed a certain distance into a fairly easily pierceable member 15 which is so shaped as to just fit snugly within the shell 16. This material of which the member 15 is made, is preferably a material such as cork.

This cork fits tightly within the shell 16, 80 and after the wires 9 and 11 are suitably inserted into the material, molten solder is poured into the shell 16, so as to preferably fill the same up to the point 18 which is the point at which the wire is no longer bare. 85 This of course, should be done while the shell is up side down, so that the molten metal will not run out.

After the molten metal has been poured into the shell, a layer of protective material 90 19 is then poured into the shell extending to the line 20. This protective material may be any of the well known insulating compounds which may be melted by heat and poured, and which will then solidify on cooling. 95 This material completely fills the shell 19 from side surface to side surface and so prevents the entrance of moisture which if allowed to enter might corrode the conductors.

After the different materials have been 100 placed into the surrounding shell 16, the whole device as 10 is moved to a position so that the mouth or opening points downwardly as shown in Fig. 1.

The shell 16 may be of many shapes, but 105 the one shown in the drawing is preferred, and it is preferred to have an enlarged skirt portion 21, so that water running down the outside surface of the shell will be guided away from the wires or conductors 9 and 11. 110

The shell 16 may be made of various materials, but it is preferred to make the shell of a nonconducting material, and preferably fiber or hard rubber.

5 Although the illustration of a specific embodiment of the invention illustrates but two conductors as connected, it is of course to be understood that as many conductors may be connected as may be inserted in the shell 10 endwise.

Although applicant has described and illustrated one particular physical embodiment only of the invention, and explained the principle and operation thereof, nevertheless, it is to be understood that the particular physical embodiment shown, is merely illustrative and does not exhaust the possible physical embodiments of means underlying the invention.

20 What is claimed as new and desired to be secured by Letters Patent of the United States, is:

1. In a connector for conductors, in combination: a shell formed with an opening at 25 one point; a wire pierceable body in the shell for receiving the bared metallic ends of conductors; a layer of solder positioned above the said body and surrounding and connecting the bared ends of conductors inserted in 30 the body and a layer of insulating material positioned over the solder and surrounding

the conductors and contacting all around the inside surface of the shell.

2. The method of making an electrical and mechanical joint between electrical conductors which consists in first inserting the ends of the conductors into a pierceable body of material inserted in a shell having one closed end and then pouring into the shell a quantity of molten solder and then pouring into 40 the shell a quantity of molten insulating material.

3. The step in the process of making an electrical connection between conductors which consists in positioning the conductors 45 adjacent by inserting the ends in a pierceable body of material.

4. The steps in the process of making an electrical connection between conductors which consists in positioning the conductors 50 adjacent by inserting the ends in a pierceable body of material, positioned in a container closed at one end and then pouring into the container a body of molten solder.

5. A shell for a connector formed as a substantially hollow right cylinder having one end closed and the other end open and the wall adjacent the open end flared to form a skirt, and provided at the closed end inside with a body of easily pierceable material for 60 the reception of the ends of conductors.

BEVERLY A. LUNDY.
